UNITED STATES PATENT OFFICE.

STEPHEN D. BAKER, OF NEW YORK, N. Y.

DESIGN FOR A GRAB RAIL OR SIMILAR ARTICLE.

Application filed December 31, 1921. Serial No. 526,393. Term of patent 14 years.

To all whom it may concern:

Be it known that I, STEPHEN D. BAKER, a citizen of the United States, and a resident of New York city, in the county of New York and State of New York, have invented a new, original, and ornamental Design for a Grab Rail or Similar Article, of which the following is a specification, reference being had to the accompanying drawings, forming part thereof.

In the drawings:

Fig. 1 is a perspective view of a grab rail embodying my design; and,

Fig. 2 is a front elevation of the grab rail shown in Fig. 1.

I claim:

The ornamental design for a grab rail or similar article as shown.

STEPHEN D. BAKER.
